(57) **CLAIM**

The ornamental design for a light-irradiating sample analyzer, as shown and described.

DESCRIPTION

FIG. 1 is a front view of the light-irradiating sample analyzer;

FIG. 2 is a perspective view of the light-irradiating sample analyzer;

FIG. 3 is a right side elevational view of the light-irradiating sample analyzer;

FIG. 4 is a left side elevational view of the light-irradiating sample analyzer;

FIG. 5 is a bottom view of the light-irradiating sample analyzer; and,

FIG. 6 is a rear view of the light-irradiating sample analyzer.
